UNITED STATES PATENT OFFICE.

EDGAR E. BROSIUS, OF PITTSBURGH, PENNSYLVANIA.

GRAB-BUCKET.

1,120,440.

Specification of Letters Patent.

Patented Dec. 8, 1914.

Application filed January 31, 1914. Serial No. 815,663.

To all whom it may concern:

Be it known that I, EDGAR E. BROSIUS, a citizen of the United States, residing at Pittsburgh, in the county of Allegheny and State of Pennsylvania, have invented a new and useful Improvement in Grab-Buckets, of which the following is a full, clear, and exact description, reference being had to the accompanying drawings, forming part of this specification, in which—

Figure 1 is a side elevation of a grab bucket embodying my invention, the crane from which the bucket is suspended and operated being shown conventionally; Figs. 2 and 3 are detail views showing the locking hook mechanism in different positions; Fig. 4 is a side elevation showing the bucket closed; Fig. 5 is an end elevation of the bucket; Fig. 6 is a detail view showing the hook and coöperating parts in another position; and Fig. 7 is a detail plan view of one of the parts. Fig. 8 is a detail view of another one of the parts.

My invention has relation to grab buckets of the clam-shell single-line type.

The object of the present invention is to provide automatic locking devices for use in connection with a bucket of this general character which will be simple and positive in their construction and operation.

The nature of my invention will be best understood by reference to the accompanying drawings, in which is illustrated the preferred embodiment thereof and which will now be described, it being premised, however, that various changes can be made in the details of construction and arrangement of the parts, without departing from the spirit and scope of my invention as defined in the appended claims.

In these drawings, the numerals 2 and 3 designate the two bucket sections having the brackets 4 at their upper inner corner portions, which are pivoted on the central shaft 5. Pivots connected to the upper outer corner portions of the bucket section 3 are the frame members 6, whose upper end portions are bent horizontally, as indicated at 7, and the extremities of these bent portions being connected to the upper outer corner portions of the bucket section 2 by the links 8. The bucket as thus far described is similar to the bucket described in my Patent No. 1,087,105, dated June 30, 1914.

The numeral 9 designates a cross head

which, in the present case, is permanently connected at 10 to the center shaft 5. Journaled on this cross head are two sheaves or pulleys 11, around which pass the end portions of the hoisting cable 12, the ends of said cable being fixed to the frame at 13. The horizontal portions 7 of the frame members 6 carry a frame 14, having at its central portion the upwardly projecting lugs or ears 15.

16 is a hook of T-shape which is pivoted at 17 between the lugs or ears 15, and has the projecting weight arm 18 at the opposite side of the pivot from its hook. The hook is formed on its under side with one locking recess 19 and with a second locking recess 20 at the opposite side of its center. Pivoted to the arm of the hook which is adjacent to the recess 20 is a gravity latch 21, which is free to swing outwardly to the position indicated in Fig. 2, but which is prevented from swinging inwardly beyond the position shown in Figs. 4 and 6 by means of a shoulder 22 on the hook arm.

23 is a transverse pin or shaft which is carried by members 24, secured to the two parts of the hoisting cable 12. In order to permit these members 24 to wind upon the drum 25 of the crane 26, which carries the bucket, each of said members may be formed in two sections pivotally connected by the pin or shaft 23.

27 is a chain or other suitable suspension member attached at its upper end to the crane 26, and carrying at its lower end a U-shaped member 28, see Fig. 8. This member 28 is suspended in a fixed position from the crane with respect to vertical movement and in position to coöperate with the hook 16 in the manner hereinafter described. The hook of the member 28 is also preferably provided with a horizontally projecting loop 29 (shown in detail in Fig. 7) and through which the hoisting cable and the members 24 are adapted to pass in the operation of the bucket.

The operation is as follows: Assuming the parts to be in the position shown in Fig. 1, in which the bucket sections are open and are ready to be lowered on to the pile of material, the cable 12 has been hoisted to a position in which the pin or shaft 23 has engaged with the recess 19 of the hook 16, thus locking the bucket sections in their open position. The bucket is now lowered

on to the pile of material and upon contacting with such pile, the slackening of the cable 12 releases shaft or pin 23 from the hook which immediately causes the weighted arm 18 of the hook 16 to swing said hook to the position shown in Fig. 2, allowing the bucket sections to close and take their load in the usual manner. When the bucket has been closed and loaded and raised to a position for dumping, the hook 16 is in the position shown in Fig. 3, having been raised to a point where its upper edge is about to contact with the transverse lower end of the U-shaped member 28; as the bucket is further raised, the lower end of the member 28 rides downwardly around the end of the hook 16 and in contact with the weighted arm 18 and when the bucket is lowered engages with the recess 20. When this engagement occurs, the bucket is suspended on the member 28 (in the manner shown in Fig. 4) and can be dumped by continuing to lower the cable 12. In dumping the bucket, the cable is lowered until the cross head 9 has moved downwardly from the position shown in Fig. 4 to the position shown in Fig. 1. During this movement, the pin 23 in going down with the cable engages the left-hand arm of the hook in the manner shown in dotted lines in Fig. 6, and passes around the nose of the hook and when the cable is raised engages the hook, thus actuating said hook to lower its weighted arm 18 and free the opposite hook from engagement with the member 28, as shown in Fig. 1. The gravity latch 21, being then substantially in the position shown in Fig. 1, prevents the reengagement of the member 28 with the hook. The parts are now again in the position shown in Fig. 1, ready for the next operation.

It will be noted that the function of the hook in one of its operative positions is to hold the bucket sections open, and that its function in the other of its operative positions is to effect a suspension for the bucket to enable it to open by the weight of its load by slackening the cable. In the first of these positions, the hook co-operates with the pin or shaft 23, carried by the hoisting cable, and in the second of these positions, it co-operates with the member 28, which is suspended at a fixed height from the crane. These operations are wholly automatic in character in that they require no special trip connections which must be actuated by the operator. The unlocking of the bucket sections in their open position is effected automatically by the contact of the sections with the pile of material without the use of any special trip paddles or other similar devices. Such devices have been found to be uncertain in their operation, owing to the different angles at which the bucket contacts with the surface of the material and are further

liable to become broken or rendered inoperative. My invention overcomes these difficulties and provides extremely simple and positive means for effecting the described operations.

It will be understood that I do not desire to limit myself to the use of my invention in connection with the particular construction of bucket which I have herein shown and described, inasmuch as it can be applied to other buckets.

I claim:

1. The combination with a grab bucket of the clam-shell single-line type having pivoted bucket sections, of a locking member pivoted to the frame of the bucket and having two hook portions located, respectively, at opposite sides of its pivot, means for normally biasing said member in a predetermined position, and means arranged to co-operate with one of said hook portions to lock the bucket sections in open position and to co-operate with the other of said hook portions to support the bucket while being dumped, substantially as described.

2. The combination with a grab bucket of the clam-shell single-line type having pivoted bucket sections, of a locking member pivoted to the frame of the bucket and having two hook portions located, respectively, at opposite sides of its pivot, a relatively fixed member supported independently of the bucket and arranged to co-operate with one of said hook portions to support the bucket while being dumped, and means for co-operating with the other of said hook portions to hold the bucket sections in open position, substantially as described.

3. The combination with a grab bucket of the clam-shell single-line type having pivoted bucket sections, of a locking member pivoted to the frame of the bucket and having two hook portions located, respectively, at opposite sides of its pivot, a relatively fixed member supported independently of the bucket and arranged to co-operate with one of said hook portions to support the bucket while being dumped, and means for co-operating with the other of said hook portions to hold the bucket sections in open position, the last named means being carried by the single line of the bucket, substantially as described.

4. A grab bucket of the clam-shell, single-line type having pivoted bucket sections, of a member pivoted to the frame of the bucket and having two hooks located, respectively, at opposite sides of its pivot, counterweighting means whereby said member normally assumes a predetermined position, and a relatively fixed member supported independently of the bucket and arranged to co-operate with one of said hook portions to support the bucket while being dumped, together with means on the single line of the

bucket to coöperate with the other hook portion and hold the bucket sections open, substantially as described.

5. In a grab-bucket of the clam shell single-line type, the combination with a frame and bucket sections pivoted to said frame, of a T-hook also pivoted to said frame, and having hook portions at opposite sides of its center and also having a portion which 10 acts to normally hold said members in a predetermined position, together with means arranged to coöperate with said hook in one position thereof to lock the bucket sections in open position, and to coöperate with the 15 hook in another position thereof to support the bucket while dumping; substantially as described.

6. A grab-bucket of the clam shell single-line type, having a frame, bucket sections

pivoted to the frame, and a hook also pivoted to the frame, said hook being provided with locking recesses at opposite sides of its vertical center and also having a weighted arm projecting to one side of its center, one of said recesses having a pivoted guard, together with means arranged to coöperate with said hook in one position thereof to lock the bucket sections in open position, and to coöperate with the hook in another position thereof to support the bucket while 30 dumping; substantially as described.

In testimony whereof, I have hereunto set my hand.

EDGAR E. BROSIUS.
